UNITED STATES PATENT OFFICE.

EDWARD J. DAY, OF MILWAUKEE, WISCONSIN, ASSIGNOR OF ONE-HALF TO OTTO H. SCHULZE, OF MILWAUKEE, WISCONSIN.

COLLAPSIBLE BASKET.

1,148,761.

Specification of Letters Patent. Patented Aug. 3, 1915.

Application filed March 2, 1914. Serial No. 821,918.

To all whom it may concern:

Be it known that I, EDWARD J. DAY, a citizen of the United States, and resident of Milwaukee, in the county of Milwaukee and 5 State of Wisconsin, have invented certain new and useful Improvements in Collapsible Baskets; and I do hereby declare that the following is a full, clear, and exact description thereof.

10 The object of my invention is to provide a simple, economical and effective wire frame collapsible basket, the invention consisting in certain peculiarities of construction and combination of parts as hereinafter 15 set forth with reference to the accompanying drawings and subsequently claimed.

In the drawings Figure 1 represents a central sectional elevation of a basket embodying the features of my invention, the 20 section being indicated by line 1—1 of Fig. 2; Fig. 2, a cross-section of the same, the section being indicated by line 2—2 of Fig. 1; Fig. 3, a detailed plan view of one corner of the basket showing the construction of 25 bottom frame, indicated by line 3—3 of Figs. 1 and 2, and Fig. 4, a detailed sectional view showing a portion of the rim frame and its connections, the section being indicated by line 4—4 of Fig. 2.

30 Referring by characters to the drawings, 1, 1, represent the longitudinal stretches of a rectangular rim frame, the said stretches being merged into end stretches 2. The longitudinal stretches are each provided 35 with spirally wound loops 1' constituting eyes for bails 3. The said longitudinal stretches 1 are also centrally cross-connected by a pair of transverse brace-bars 4, 4, to which brace-bars are hingedly secured U- 40 shaped lid frames 5, the same being covered by a sheathing 6 of fabric or other suitable material. The bottom of the basket is formed by a rectangular bottom frame having longitudinal stretches 7 connected by 45 transverse stretches 7' as shown and connecting said transverse stretches is a longitudinal stay-bar 8, which stay-bar is secured by looped heads that overlap the stretches 7, the said stay-bar being centrally disposed 50 relative to the side stretches of the bottom frame. The transverse stretches 2 of the rim frame have hingedly connected thereto U-shaped end frames, the vertical stretches 9 of which are connected by transverse 55 stretches 9', which bottom stretches, as best

shown in Fig. 2, are bowed downwardly in opposite directions from an imaginary central line. The apex of the bow is adapted to engage the longitudinal stay-bar 8 of the bottom frame when the end frames are 60 distended or swung to a position for expanding the basket into shape for loading. Thus the bottom stretches 9' of the end frame 9 constitute flexible stretchers and, owing to the fact that there is slight spring 65 in the metal, the frictional engagement between the bottom stretches 9' and longitudinal stay-rod 8 is sufficient to hold the frame in its distended position. It is understood that the heads of the stay-bars 8 form stops 70 for the bowed bottom stretches of the end frames when said frames are distended. The rim frame and bottom frame are incased in a sheathing 10 forming the bottom, side and end walls of the basket, the said sheathing 75 being preferably formed from some porous material such as cotton, silk, canvas or any woven cloth. It is understood, however, that in some instances the sheathing may be composed of waterproof material. 80

From the foregoing description it is obvious that when the basket is not in use, it can be folded into a flat, compact body so as to be conveniently carried, the folding being obtained by swinging the free end members 85 of the frame upwardly toward the rim member, which end members are adapted to fold one within the other, as best shown in dotted lines. Thereafter the bottom frame member is nested against the rim frame member 90 with the sheathing material folded inwardly. These baskets may be of any desired dimensions and may be used for various purposes such as, for example, lunch baskets, or they may be utilized as package retainers for the 95 convenience of shoppers or for marketing or any other purpose to which such devices are applicable.

I claim:

1. A wire frame collapsible basket comprising a rectangular rim frame and a rectangular bottom frame, a centrally disposed stay-bar having heads connecting the transverse stretches of the bottom frame, U-shaped end frames in hinge connection with the transverse stretches of the rim frame, the free transverse bottom stretches of said end frames being bowed upwardly and adapted to yieldingly engage the stay-bar to constitute stretches when the basket is 110

distended, movement of the bowed portions being limited by the stay-bar heads, and a flexible sheathing for the bottom, side and ends of the frame, the sheathing being secured to the rim frame member.

2. A wire frame collapsible basket comprising a rim member having side stretches bent upon themselves to form companion loops, a rectangular bottom frame, a centrally disposed longitudinal stay-bar connecting the transverse stretches of said bottom frame, U-shaped end frames in hinge connection with the transverse stretches of the rim frame, the free transverse stretches of the end frames being bowed upwardly

for engagement with the stay-bar to constitute stretches when the basket is distended, and a flexible sheathing for the bottom, side and ends of the frame, the sheathing being secured to the rim frame member, and a 20 pair of bails in hinge connection with the loops of the rim frame.

In testimony that I claim the foregoing I have hereunto set my hand at Milwaukee in the county of Milwaukee and State of Wisconsin in the presence of two witnesses.

EDWARD J. DAY.
